UNITED STATES PATENT OFFICE.

JOHN F. O'CONNOR, OF CHICAGO, ILLINOIS, ASSIGNOR TO WILLIAM H. MINER, OF CHICAGO, ILLINOIS.

BUMPER-POST FOR RAILWAY-SERVICE.

1,070,059.

Specification of Letters Patent. Patented Aug. 12, 1913.

Application filed September 13, 1912. Serial No. 720,147.

To all whom it may concern:

Be it known that I, JOHN F. O'CONNOR, a citizen of the United States, residing in Chicago, in the county of Cook and State of Illinois, have invented a certain new and useful Improvement in Bumper-Posts for Railway-Service, of which the following is a full, clear, concise, and exact description, reference being had to the accompanying drawings, forming a part of this specification.

My invention relates to improvements in bumper posts for railway service.

The object of my invention is to provide an efficient and durable bumper post, and one which will perform its service without injury to cars or other railway equipment.

In the accompanying drawings forming a part of this specification, Figure 1 is a front elevation partly in transverse section of a bumper post embodying my invention. Fig. 2 is a side elevation thereof. Fig. 3 is an elevation view partly in vertical section of the shock-absorbing member. Fig. 4 is a front elevation of the shock-absorbing member, partly in transverse section on line 4—4 of Fig. 3, and Fig. 5 is a cross section on line 5—5 of Fig. 3.

Referring to the drawings, 6 represents a bumper post frame adapted to be secured at the end of a railroad track, or between the rails thereof.

7, 7 are the rails of a railroad track.

The frame 6 is provided with a base consisting of the two parallel members 8, 8, preferably channel beams.

9, 9 are front legs which extend from the forward end of base channels to top of post.

10, 10 are lateral plates connecting the base members 8, 8 and the front legs 9, 9 with the member 11, preferably a channel beam which forms the top and rear end of the post and joins the two sides of the structure.

14, 14 are rivets joining the parts of the structure.

I prefer to provide a comparatively large base for the frame and to curve the front legs thereof forwardly, as illustrated at numeral 15 in Fig. 2.

The legs of the frame are of a suitable height to permit of mounting between them and within the forwardly open recess 16 in the frame and parallel to the railroad track upon which the bumper post may be em-

ployed, the shock-absorbing member 17 at a height coincident with that of the coupler of a railway car. The shock-absorbing member has a spring case 18 laterally provided with the flanges 19, 19, which are 60 suitably bolted to the sides of the post. The spring case 18 contains the coil springs 20, 20, preferably four in number. The sides of the spring case conform substantially to the outer contour of the assembled springs, 65 as illustrated in Fig. 5. The spring case is closed at its rear end by the preferably integral plate 21, and open at its forward end. Around its forward end is provided the outwardly extended flange 22. The friction shell 23 is preferably a hollow cylinder 70 in shape, open at either end, and provided with an internal friction face 24. At its rear end the friction shell is provided with the circumferentially outwardly extended 75 flange 25, suitably provided with perforations registering with similar perforations in the flange 22 of the spring case to permit the passage of the bolts 26 employed to secure the friction shell to the spring case. 80

In preferable construction the rear face of the flange 22 of the spring case is substantially flush with the front faces of the forward legs of the frame, and is bolted thereto by means of bolts 27. The friction shell 85 projects forwardly therefrom. It is also preferable to further secure the friction shock-absorbing member by the U-shaped strap 28 riveted to the frame at its ends 29, 29, and encircling the friction shell at its 90 other end. Within the friction shell 23 is the spring 30 seated at its rear end against the movable spring seat or plate 31, and at its forward end against the shoulders 32 with which the annularly arranged 95 segmental friction shoes 33 are provided. The friction shoes are preferably three in number, and are each outwardly provided with an external friction face 34. The inner surface of each is provided with the wedging face 35 between which and the adjacent wedging face 36 of the wedge 37 is disposed an anti-friction roller 38. The wedge is of a general pyramidal shape and provided with wedging faces equal in number to the 100 number of friction shoes, and having at its forward end an enlarged head or buffer 39. Forwardly the wedge is provided with a central recess 40 to receive the head 41 of the connecting rod 42 which extends through 110

a perforation 43 in a rearwardly extended central portion 44 of the wedge and through the perforation 45 in the movable spring seat 31, which is provided in its rear face with a recess 46 to receive the nut 47 of the connecting rod. The movable spring seat 31 is provided circumferentially with a forwardly extended ring 48, which upon compressing movement of the shock-absorbing member limits the compression of the spring 30 by engagement with the rear ends 49 of the friction shoes. The springs 20, 20 are seated at their forward ends against the rear face 50 of the movable spring seat 31, and at their rear ends against the rear end of the spring case.

I claim:

1. A bumper post comprising a frame to receive a shock-absorbing member, a shock-absorbing member secured to the said frame, the said shock-absorbing member comprising a spring case and springs within the case, a friction shell secured to said spring case, friction shoes and wedge, and a spring within the shell, a movable spring seat between the said spring and the springs within the spring case, the said movable spring seat being provided with a forwardly extended ring to engage the friction shoes on compressing movement and limit the compression of the spring within the friction shell.

2. In a device of the character described, a shock absorbing member comprising a shell,

friction shoes and springs within the shell, 35 a wedge engaging the friction shoes, the said wedge having a head adapted to engage the front end of the shell and limit the compressing movement of the friction shoes and springs within the shell.

3. A shock absorbing device comprising a spring case, springs within the spring case, a friction shell secured to the spring case, friction shoes and wedge and spring within the shell, a movable spring seat engaging 45 said spring at one end, and having a forwardly projecting member adapted to engage the friction shoes on compressing movement, and limit the compression of said spring.

4. In a shock absorbing device, a spring case and a friction shell connected thereto, springs within the spring case, friction shoes, a wedge and spring within the shell, a movable spring seat between the springs 55 within the spring case and the spring within the shell, said spring seat being provided with a forwardly projecting member to engage the friction shoes on compressing movement, and limit the compression of the 60 spring within the shell, the wedge being provided with a head to engage the shell on compressing movement, and to limit the movement of the parts within the shell.

JOHN F. O'CONNOR.
